UNITED STATES PATENT OFFICE

CHARLES I. ALLEN, OF WADESBORO, NORTH CAROLINA

LEG SPLINT

Application filed April 24, 1930. Serial No. 446,910.

This invention relates to an improved leg splint to be used in the treatment of fractures of the leg and thigh.

It is an object of my invention to provide a splint for use in treating fractures of the leg and thigh of a human, in which means are provided for holding the leg in such a position as to cause a proper healing of the fracture, and to provide means for applying traction to the leg to cause the fracture to heal properly and to hold the fractured parts in proper position during the healing operation.

Another object of my invention is to provide an improved leg splint for the treatment of fractures, in which means are provided for suspending the leg and for holding the leg in proper position, and to present a minimum of resistance to the traction which is applied to the leg during the treatment of the same, and means are also provided for indicating the amount of traction which is applied to the leg, together with means for holding the foot in proper position during the treatment.

Another object of my invention is to provide a leg splint having means for applying traction to the side portion of the leg where the fracture appears above the knee and for permitting adjustment of the lower leg portion below the knee to allow it to be suspended at various angles as desired.

Another object of my invention is to provide a leg splint for supporting a fracture in any desired adjusted position.

Some of the objects of my invention having been stated other objects will appear as the description proceeds, when taken in connection with the accompanying drawings, in which—

Figure 1 is a side elevation of my device showing a leg held in position therein;

Figure 2 is a plan view of Figure 1 showing only a portion of the leg in position;

Figure 3 is a side elevation of the lower end of a modified form of my splint;

Figure 4 is an enlarged detail view taken along the line 4—4 in Figure 2;

Figure 5 is an end view of Figure 1 taken along the line 5—5 in Figure 1;

Figure 6 is an elevation of the foot rest taken along the line 6—6 in Figure 1;

Figure 7 is a cross-sectional view taken along the line 7—7 in Figure 1;

Figure 8 is a cross-sectional view taken along the line 8—8 in Figure 1;

Figure 9 is an enlarged plan view of the spreader means for holding the tape for traction purposes;

Figure 10 is a cross-sectional view taken along the line 10—10 in Figure 9;

Figure 11 is a perspective view of the means for connecting the side bars to the ring member;

Figure 12 is a perspective view of one of the cuffs slidably mounted on the side bars;

Figure 13 is a view partially in cross section and showing the means for registering the traction applied to the leg.

Figure 14 is a modified form of my invention in which traction is applied to the upper portion of the leg and an attachment is secured intermediate the side members to adjust the lower portion of the leg;

Figure 15 is another modified form of my invention in which no traction is applied but the device is used to support a leg and act in the form of a brace;

Figure 16 is a view similar to Figure 15 but showing means for suspending the leg in adjusted position;

Figure 17 shows an adjustable support adapted to be used in connection with Figure 15;

Figure 18 is a plan view of a supporting member adapted to be used in lieu of cuffs 36 and webbing 43;

Figure 19 is a side elevation of Figure 18.

Referring more specifically to the drawings the numeral 10 indicates a human's thigh with the lower portion of the leg being designated by the reference character 11, and the foot being designated by the reference character 12. It is a well known fact that when a fracture occurs in a leg that the muscles of the leg pull the two ends of the bone into an overlapping position and it is the purpose of this invention to prevent this overlapping position of the ends of the bone, and to cause the ends of the bone to fit

against each other as near as possible in the original position before the breakage occurred. To this end I provide the ring-shaped member 13 which has the projections 5 14 and 15 on one side thereof into which can be screwed the rods 16 and 17 to prevent the device and the leg carried thereby from turning while in position on the patient as these parts 16 and 17 fit against the bed on which 10 the patient is reclining. On the other side of the ring member 13 I provide projections 18 and 19 which likewise have holes internally threaded therein which are adapted to receive the threaded rods 16 and 17 when the 15 device is used on the right leg, as it is shown in position on the left leg in the drawings. This ring member 13 has a downwardly curved portion 20 which is adapted to cause a better fitting of the ring member around 20 the upper leg portion of the patient as this indentation 20 prevents undue pressure from being applied to the pubic bone of the patient. This member 13 is covered with rubber or 25 any other suitable material such as 21, and if desired a thin covering 22 such as a sanitary tape or other means can be placed on the outside of the portion 21.

Projecting rigidly from the portion 20 of ring 13 is the portion 23 and also projecting 30 from the other side of the ring member is the projection 24. The projection 24 has pivotally mounted therein the member 25 which members 23 and 25 have threadably secured 35 therein the bolt 26. Hollow bar members 27 and 28 are adapted to slidably fit over the members 23 and 25, said bar members having the slot 29 therein which is adapted to slide past the screw 26, and when screw 26 is tightened it will rigidly hold the bar members 27 and 28 to the respective portions 23 and 25. This arrangement is provided in 40 order for bars of different length to be used for patients having different lengths of legs, as it is evident that each individual patient 45 will require a certain specified length of bars such as 27 and 28.

The bars 27 and 28 have the other ends thereof sold and holes are provided in the solid ends into which the screws 32 and 33 50 are secured, said screws penetrating holes 34 and 34 in a member 35, said member 35 being adapted to hold in adjusted position the free ends of the bars 27 and 28. It is seen 55 that the width of these bars 27 and 28 is adjusted by means of the member 35 and the screws 32 and 33.

Slidably mounted on the bars 27 and 28 are 60 a plurality of cuff members 36, said cuff members being more plainly shown in Figure 12. These cuff members 36 have the upwardly projecting portion 37 in which the slots 38 and 39 appear, and these cuff members are 65 adapted to encircle the bars 27 and 28 and to slide there along. On the outer side of the

members 36 are the projections 40 and 41, in which the buckle member 42 is pivotally mounted, said buckle member 42 being adapted to hold in adjusted position the webbing or tape member 43. This webbing or tape member 43 is adapted to be held by the buckle members 42 to suspend the leg of the patient in the splint. I have indicated by the reference character 43 in Figure 1 the use of the webbing or tape merely to support the leg of the patient, and in the central portion of Figure 1, which is shown more fully in Figure 7 I provide the webbing 45, which is secured in the buckle on one of the cuffs and runs beneath the leg and into the slot 39 and back through the slot 38, and again beneath the leg and then around the top of the leg and back into the buckle portion which permits side pull to be applied to the leg. This allows lateral pressure to be applied to the leg to hold the same in proper position as where the leg would have a tendency to heal in a crooked condition. This arrangement can be used on any of the buckles but I have shown it applied to only one of them.

It is evident that these cuffs and web supports are adapted to slide along the bar members and offer a minimum of resistance to the traction applied to the leg. This traction is applied by providing a set of cuffs 50 and 51 95 on the bars 27 and 28. These cuffs 50 and 51 have vertically disposed grooves therein into which the foot board member 52 is adapted to be placed, and this foot board member has a plurality of slots 53 through which a belt or web or tape 54 is passed and secured around the upper portion of the foot of the patient by means of the buckle 55.

The lower portion of the foot board 52 has slots 60 and 61 therein through which the tape portions 62 and 63 are adapted to pass, said tape portions 62 and 63 being adapted to be applied to the side of the leg to exert a traction on the leg to hold it under proper tension while the healing operation is being completed. These tapes 62 and 63 are applied in connection with the wrappings or bandages 64 which are a conventional method of treatment in fractures, but I provide the tapes 62 and 63 and pass them out through the holes 60 and 61 and secure them in the buckles 65 and 66, which are in the ends of the member 67, this member 67 being a spreader member and being adapted to prevent any pressure from being made on the ankle bone by 120 the tape members furnishing means of obtaining the traction on the leg. Near the central portion of this member 67 is an eye 68 into which a hook 69 is adapted to be secured, and in one form of the invention I show a 125 scale or registering device 70 secured to this hook with a hook 71 secured to the other end of this registering device 70 which passes through the central portion of member 36 and has a nut 72 secured thereon by means of 130

which a certain given traction can be applied to the leg of the patient.

This registering device is shown more fully in Figure 13, in which the casing 70 has the movable casing 74 therein, in which the eye member 75 is secured which is secured to the link 69. A tension spring 76 is secured on the inside of this cylinder 74 and the other end of this tension spring is secured as at 77 to the plug member 78 which closes up the end of the cylinder 70 and has the eye member 79 secured therein to which the member 71 is secured. In a modified form of this invention as shown in Figure 3, I may dispense with the registering device, but provide instead thereof the cord 80 which is adapted to be secured to the spreader member 67 which cord 80 passes around a pulley 81 and has a plurality of weights 82 adapted to be placed on the lower end of said cord 80 to apply the proper traction to the leg of the patient. It is evident that when the free ends of the bars 27 and 28 are adjusted apart from each other to a wider degree than that shown in Figure 2, that for each adjustment a separate foot board will have to be used as the foot board must be of proper width to fit the adjustment of the bars 27 and 28.

There is some play between the foot board and the cuff members 50 and 51 which it is carried, so as to allow a slight movement of the foot and foot board with relation to the cuff members.

The metal cuffs which have previously been described for holding webbing for supporting the leg in any position are adjustable to any position on the bars and can be used on either bar by reversing them as to position.

The purpose of the foot piece or foot board which has previously been described is to hold the foot in an erect position and to prevent what is called "foot drop."

It is thus seen that I have devised a splint which may be used for either leg and is adjustable to any size and length of leg by using various size rings and lateral bars of various lengths. It is seen that it is so arranged that the splint can not turn to the right or left and that the bars 16 can be removed when it is desired for the patient to use the bed pan, and also that the splint prevents the leg from being turned to the right or to the left. It is also seen that the foot is held in upright position and can not turn to the right or left thus keeping the leg and foot in their proper position with relation to the body at all times. It is also seen that the arrangement is such that the under-surface of the ring is held up against the pubic bone which is the most suited part to bear the tractive pressure, and that by use of the square type lateral bars and metal cuffs with buckles and slots an arrangement has been devised to hold the webbing which supports the leg between the bars which permits an easy adjust-

ment and that lateral pressure if desired can be applied, and the webbing and the metal cuffs do not offer much resistance to the tractive force. It is seen that by using metal cuffs with a slot arrangement which carries the metal foot piece of various widths to suit the width between the lateral bars there are efficient means for holding the foot up and preventing it from turning either to the right or left, and by providing a foot piece through which the tractive tape passes and offers no resistance to the tractive force that an advancement has been made.

Furthermore it is seen that by having buckles on the adhesive spreader a simple and efficient means has been devised to hold the adhesive to permit easy adjustments and to prevent the adhesive from pressing on the ankle. The splint is also arranged so that the tractive pull may be made by a cord and weight or by a spring scale as desired, as it is evident that either form of tractive pull may be employed to suit particular conditions.

In the modified form of my invention as shown in Figures 14 to 17 inclusive I provide the structure as shown in the previous figures in Figure 14 and in addition thereto where the traction is desired to be applied to the upper portion of the leg or the side portion, I have the same arrangement as shown in the preceding figures, but in addition thereto I provide the cuff members 100 on each side of the knee portion which are secured to the bars 27 and 28 by means of a thumb nut and screw 101 and on the lower side of these cuffs 100 are adjustably secured by means of thumb nut and bolt 102 the side bars 112 which have the conventional cuffs 36 thereon for supporting the lower portion of the leg, and the conventional foot board as previously described and I provide the cord 103 for suspending the lower portion of the leg so that it can be adjusted vertically and still traction can be applied to the side portion of the leg. The other parts in Figure 14 not described are identical to the parts heretofore described.

In Figure 15 I show a modified form of my invention in which I have the conventional ring member 13 and associated parts but the side bars are shorter than in the previous forms of my invention as shown, said side bars being designated by the reference character 115, and these side bars have the conventional cuffs and supporting means as previously described, and have the conventional bar 35 across the free end thereof for supporting the free end of said bars 115. Near the knee portion I provide the structure which has previously been described and as shown in Figure 14, but the lower end of this attachment is adapted to rest on the bed and a brace member comprising the U-shaped part 105 which is tubular and the hooked rods 106 and 107 are adapted to be adjustably

secured therein by means of the screws 108 for supporting the knee portion of the device at any desired height above the bed as shown in Figure 15.

- 5 In Figure 16 I show the identical structure as shown in Figure 15, with the exception that I dispense with the support 105 and associated parts and provide the cords 110 and 111 by means of which the position of the leg of
10 the patient can be adjusted by regulating the cords 110 and 111.

In Figures 18 and 19 I show a modified form of the supports for the leg which consist of the member 120 which has the downwardly projecting portions 121 and 122 at one end thereof and the projections 123 and 124 at the other end thereof which projections are adapted to fit over the side bars 27 and 28.

It might also be stated in this application
20 that I have devised a leg splint having bars rectangular in cross-section for heretofore all splints of this nature have been round or of the similar nature and by providing the side members rectangular in cross-section I prevent any turning movement of the supporting means for the leg.

In the drawings and specifications I have set forth a preferred embodiment of my invention, and although specific terms are employed, they are used in a generic and descriptive sense only, and not for purposes of limitation, the scope of the invention being set forth in the appended claim.

I claim:

- 35 A leg splint having a limb encircling ring and track members secured to said ring to occupy positions on opposite sides of the leg, a plurality of slideable web holding cuffs mounted on said track members, means for preventing turning movement of said cuffs on said track members, each of said cuffs having a buckle therein and also having an upwardly projecting portion integral therewith, said upwardly projecting portions having two spaced horizontally disposed slots therein whereby a piece of webbing can be secured in the buckle on one cuff and extend beneath the leg then out through the lower slot in the other cuff on the other side of the leg, then
40 back through the top slot in said other cuff, then again beneath the leg and over the top of the leg and then over the top of said projection in said other cuff and through the buckle in said other cuff to apply lateral traction to the leg.
- 50
- 55

In testimony whereof I affix my signature.
CHARLES I. ALLEN.
